(57) **CLAIM**

The ornamental design for a fastening buckle for socket rail organizer tray as shown and described.

DESCRIPTION

FIG. 1 is an upper perspective view of a fastening buckle for socket rail organizer tray showing my new design;

FIG. 2 is a front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof;

FIG. 8 is a lower perspective view thereof; and,

FIG. 9 is an upper perspective view showing the fastening buckle for socket rail organizer tray in a condition of use. The broken lines of FIG. 9 illustrate environmental matter and form no part of the claimed design.
